CLAIM

The ornamental design for a spikeless cleat, as shown and described.

DESCRIPTION

FIG. 1 is a perspective view of the spikeless cleat showing my new design;

FIG. 2 is a top plan view thereof;

FIG. 3 is a side view thereof, each of the side views rotated 120 and 240 degrees thereof are identical thereto;

FIG. 4 is a bottom plan view thereof; and,

FIG. 5 is another side view thereof, each of the side views rotated 120 and 240 degrees thereof are identical thereto.
